(57) **CLAIM**

The ornamental design for an audio cabinet, as shown and described.

DESCRIPTION

FIG. 1 is a perspective view of an audio cabinet according to the claimed design;

FIG. 2 is a second perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an enlarged perspective view thereof;

FIG. 10 is an enlarged perspective view of the perspective of FIG. 1 taken at area X;

FIG. 11 is an enlarged perspective view of the perspective of FIG. 2 taken at area XI;

FIG. 12 is an enlarged elevation view of FIG. 3 taken at area XII;

FIG. 13 is an enlarged elevation view of FIG. 5 taken at area XIII; and,

FIG. 14 is a further enlarged elevation view of FIG. 13 taken at area XIV.

Broken lines are environmental only and form no part of the claimed design.

Dash-dot-dash broken lines adjacent un-shaded areas represent bounds of the claimed design and form no part of the claimed design themselves.

1 Claim, 14 Drawing Sheets
